UNITED STATES PATENT OFFICE

2,206,346

PRESSURE CATCH

Charles R. Crosno, Albuquerque, N. Mex.

Application March 14, 1938, Serial No. 195,885

1 Claim. (Cl. 292—76)

This invention relates to new and useful improvements in door catches generally, although more particularly to those embodying a spring tongue.

5 The principal object of my invention is to provide a door catch having a spring tongue adapted to be yieldably engaged by a door to hold the latter in a closed position.

Another object of my invention is to provide 10 a single device of the above character which is adapted for use with a pair of doors whereby each door can be yieldably retained in a closed position independently of the other.

With these and other objects in view which 15 will more fully appear, the nature of the invention will be more clearly understood by following the description, the appended claim, and the several views illustrated in the accompanying drawing.

20 In the drawing:

Figure 1 is a fragmentary front elevation of a door and casing showing the application of a door catch constructed in accordance with my invention.

25 Figure 2 is a similar view except that my door catch is shown applied to the door jamb.

Figure 3 is a fragmentary front elevation showing my door catch applied to a door jamb for use with a pair of doors.

30 Figure 4 is a transverse section taken on line 4—4 of Figure 1.

Figure 5 is a transverse section taken on line 5—5 of Figure 2.

35 Figure 6 is a front elevation of one form of my invention.

Figure 7 is a sectional view taken on line 7—7 of Figure 6.

Figure 8 is a sectional view taken on line 8—8 of Figure 7.

40 Figure 9 is a similar view of another form thereof.

Figure 10 is a front elevation of another form of my invention.

45 Figure 11 is a sectional view taken on line 11—11 of either Figure 9 or Figure 10, and

Figures 12, 13, 14 are end elevations of door catches showing modifications of the shapes of the resilient tongues.

Like reference numerals designate corresponding parts throughout the several figures of the drawing.

Referring to the drawing in detail, my invention is embodied in a door catch A for a door casing installation with single doors, a door catch B for door casing installation for double doors,

a door catch C for door jamb installation for single doors, and a door catch D for door jamb installation for double doors.

The door catch A, as shown in Figs. 1, 4, 6, 7 and 8, is formed from a piece of resilient sheet metal which is bent transversely intermediate its ends to form an upstanding attaching flange 5 and a laterally extending yieldable door-engaging tongue 6, the flange and the tongue being disposed in substantially right angular relation to each other. The flange 5 is provided with an opening 7 for receiving a holding screw 8. The tongue 6 is bowed downwardly as shown in Figs. 4 and 7 to form a downwardly inclined front end portion 9, a centrally disposed long flat door-engaging portion 10, and an upwardly inclined rear end portion 11, the front end portion 9 joining the flange 5 through the medium of a rearwardly extending flange 12 which cooperates with the flange 5 to conjointly form a right angle structure.

In Figs. 1 and 4, I have shown a door casing 13 having a transverse bar 14, and a door 15 hinged-ly mounted in the casing. The door catch A is mounted on the bar 14 with the attaching flange 5 on the exterior surface of the bar 14 and the flange 12 disposed against the under surface of the bar. As the door 15 is being closed the edge of the door contacts the front end portion 9 which acts as a cam to flatten the door-engaging portion upon continued movement of the door. When the door is fully closed the door-engaging portion 10 is in surface contact with the upper face of the door. The end of the upwardly inclined rear end portion 11 does not contact the door and consequently when the door is opened the end of the tongue 6 will not mar the wood of the door. As the door is being closed, the direction of travel of the door relative to the catch is from the attaching flange 40 to and along the tongue of the catch. By reason of the attachment of the flange to the outer face of the door casing, the catch is prevented from bodily movement as the edge of the door contacts the inclined cam surface 9.

The door catch B, as shown in Figs. 3 and 9, is formed from a piece of resilient sheet metal which is bent transversely to form an upstanding attaching flange 16 and spaced parallel laterally extending yieldable door-engaging tongues 17, 17, the flange and the tongues being disposed in substantially right angular relation to each other. The flange 16 is provided with a pair of openings 18, 18 for receiving holding screws 19, 55

19. Each tongue 17 is bent to the same configuration as the tongue 6 of the catch A.

In Fig. 3, I have shown the top bar 20 of a door casing and a pair of cooperating doors 21, 5 21 mounted in the casing. The door catch B is mounted on the bar 20 and is symmetrically disposed relative to the meeting edges of the two doors. The attaching flange 16 is located on the exterior surface of the bar 20 and the 10 tongues 17, 17 are disposed against the under surface of the bar and respectively over the doors. Thus it will be seen that either door may be opened or closed independently of the other, and that in so doing the action of the top of each door 15 upon its cooperating tongue 17 is the same as the tongue of the catch A.

The door catch C, as shown in Figs. 2 and 5, is similar to the door catch A, but the upstanding attaching flange of the catch C is of lesser height 20 than that of the catch A, whereby the catch C is adapted to be installed on the door jamb of a single door.

The door catch D, as shown in Figs. 10 and 11, is similar to the door catch B but the upstanding 25 attaching flange of the catch D is of lesser height than that of the catch B, whereby the catch D is adapted to be installed on the door jamb of double doors.

In Figs. 12, 13, and 14, I have shown several 30 modified catches E, F and G respectively.

In Fig. 12, I have shown a door catch E formed from a piece of sheet metal bent transversely intermediate its ends to form an upstanding attaching flange 22 and a laterally extending 35 tongue 23 which is bent transversely to a flat V-shape as seen in side elevation. In Fig. 13, I have shown a door catch F similar to the door catch E and including an attaching flange 24 and a tongue 25 similar to the tongue 6 of the 40 catch A but having its free end extending up-

wardly. In Fig. 14, I have shown a door catch F similar to the door catch E and including an attaching flange 26 and a downwardly extending curved tongue 27 as seen in side elevation.

Thus it will be seen that I have formed a door 5 catch which is operable with a single door whereby the door will be frictionally held in a closed position, or with double doors whereby both doors will be frictionally held independently in closed 10 positions.

It is of course to be understood that the 15 details of structure and arrangement of parts may be variously changed and modified without departing from the spirit and scope of my invention.

I claim:

A door catch of resilient sheet metal bent intermediate its ends to form an upstanding attaching flange and a laterally extending yieldable door-engaging tongue, said tongue being 20 bowed downwardly to form a downwardly inclined front end portion, a centrally disposed flat door-engaging portion, and an upwardly inclined rear end portion, said front end portion joining said attaching flange to conjointly form 25 a right angled structure, whereby the attaching flange is secured exteriorly of the door casing and with the said door-engaging tongue interposed between the inner edge of the door casing and the said door in a manner whereby no parts 30 project beyond the outer plane of the said door casing, and wherein the downwardly inclined front end portion and the upwardly inclined rear end portion of the door engaging tongue are adapted to bear against the door casing at spaced 35 points to hold the said door engaging portion in resilient frictional engagement with the said door.

CHARLES R. CROSNO. 40
